UNITED STATES PATENT OFFICE.

LOUIS SCHLESINGER, OF MILWAUKEE, WISCONSIN.

SPACING MECHANISM FOR TYPE-WRITING MACHINES.

SPECIFICATION forming part of Letters Patent No. 738,492, dated September 8, 1903.

Application filed April 10, 1902. Serial No. 102,251. (No model.)

To all whom it may concern:

Be it known that I, LOUIS SCHLESINGER, a citizen of the United States, and a resident of the city and county of Milwaukee, State of Wisconsin, have invented certain new and useful Improvements in Spacing Mechanism for Type-Writing Machines, of which the following is declared to be a full, clear, and exact description.

- 10 The improvement relates to spacing mechanism for type-writing machines, whereby the paper or other carriage may be released from its escapement and its free run in the direction of the line of print arrested at a predetermined point. Such a spacing mechanism usually comprises two coacting members—viz., a series of stops and means for dogging said stops.
- 15 The primary object of the invention is to provide a construction in which the stops are separably adjustable and arranged to be set in adjusted position to define columnar positions at different points along the line of print, and in which one of the coacting members is carried upon a shiftable or rotatable part which is mounted upon the machine-frame independently of the paper or other carriage, but connected thereto to shift as the carriage travels in the direction of the line of print,
- 20 and to arrange such a construction so that any one of a series of column-fields arranged along the line of print may be selected at a single operation, thus skipping all intermediate column-fields between the starting-point and the particular one at which the entry is to be made.

- 25 Another object of the invention is to provide finger-key mechanism for effecting the engagement of the dogging means with the stops and for automatically detaining the parts in shifted position independently of the key mechanism, whereby the operation of the mechanism independent of the continued pressure of the operator's finger upon the key is assured.

- 30 A still further object of the invention is to provide releasing means for the carriage, which is arranged to operate only after the operator has released the key mechanism, so that the 35 premature run of the carriage before the stop mechanism is in position is prevented.

Other objects of the invention will herein-after appear.

The invention consists in the combinations and arrangements of parts and the features 55 of construction hereinafter set forth, illustrated in the accompanying drawings, and more particularly pointed out in the appended claims.

In the drawings, Figure 1 is a side elevation of a type-writing machine of the Remington type with my improved spacing mechanism applied and with parts shown in section. Fig. 2 is a rear elevation of the same. Fig. 3 is a partial plan view with the carriage 60 omitted for the sake of clearness. Fig. 4 is a vertical section on line 4 4 of Fig. 3. Fig. 5 is a vertical section on line 5 5 of Fig. 3. Fig. 6 is a vertical section on line 6 6 of Fig. 3. Fig. 7 is a detail rear elevation of the carriage-release mechanism in shifted position. Fig. 8 is a detail plan view of the stop-dog and the operating parts. Fig. 9 is a vertical detail section on line 9 9 of Fig. 8.

The improvement is shown as applied to a 75 type-writer of the Remington type; but it will be understood that it may be applied to various other styles of machines and not only to those in which the shifting carriage carries the paper-support, but as well to those in 80 which the shifting carriage carries the printing mechanism and travels over a fixed paper-support, the invention being designed to arrest at predetermined points the travel of a carriage of any suitable type.

In the drawings many of the usual and well-known features of the type-writer are omitted for the sake of clearness. The base or main frame A of the machine carries the top plate a upon corner-uprights 10. The 90 cylindrical platen C is journaled within a platen-frame 11, which is supported by a front roll 12, traveling on a cross-rail 12^a, fixed above the top plate and connected or hinged at its rear end to a carriage B. The carriage 95 B is mounted upon rolls 13, engaging the cross-rail 14, fixed in position above the rear portion of the top plate a. A rearwardly-extending horizontal arm b is fixed to the carriage B, and its rear forked end engages a collar 15, 100 mounted to slide upon a cross-rail 16, which is fixed between uprights 16^a, rising from top

plate *a*. The usual pivoted margin stop-bar *D* extends between the uprights *16*^a beneath cross-rail *16*. Carriage *B* is propelled in the direction of the line of print by a spring-
5 actuated barrel or drum *E*, fixed to the inner end of a horizontal shaft *17*. The latter is journaled within a tubular sleeve *18*, which in turn is mounted to revolve within a bearing *19*, formed on the end of a laterally-projecting portion *20* of a bracket *21*, which depends from the under side of top plate *a*. A coiled actuating-spring *e* is connected at its outer end to the drum or barrel *E* and at its inner end to the inner end of sleeve *18*. The usual
10 *ratchet-wheel* *22* is held upon the outer end of the sleeve *18* by a nut *22*^a and is engaged by the double retaining-pawl *23*, which is mounted on the center pivot *24*. The carriage drive-strap *e'* extends about the drum
15 *E*, and its free end engages a hook *25*, fixed to and depending from the carriage *B*. The carriage-escapement rack *27* is fixed in the usual manner to arms *28*, which are pivoted at *29* to the carriage, so that the rack may be
20 swung upward and released from the pinion *30*, with which it normally engages. The latter is fixed upon the forward end of a shaft *31*, which is journaled within a suitable housing *32*, fixed upon top plate *a*. The escapement
25 *ratchet-wheel* *33* is mounted upon the rear outer end of shaft *31*, the teeth of which are engaged by the dogs or pawls *34* and *35*, mounted upon the upwardly-extending arm *36* of the dog-rocker. The latter is journaled
30 between rearwardly-projecting ears *37* upon the bracket *21* and is provided with a forwardly-projecting arm *38*, connected to the universal bar of the machine, so that the carriage travels step by step in the direction of
35 the line of print as the keys are operated in the usual manner. The driving barrel or drum *E*, over which the carriage drive-strap *e'* is wound, is preferably cam-shaped, as clearly indicated in Fig. 4, so that the pull
40 upon the carriage will be uniform at all times in spite of the diminishing tension of the drive-spring *e* as the carriage moves to the left.

The parts thus far described are well known
50 in the Remington No. 6 type-writing machine, and their construction need not be more particularly set forth.

Upon the rearwardly-projecting end of the shaft *17* is carried a wheel or disk *F*, which
55 serves as a mount for the column-field stops *G*. The disk is preferably provided with a series of radial slots or seats *f* in its periphery for the stops, and these slots or seats are spaced to correspond with the various spaced positions of carriage *B*. If the drive drum *E* upon which the carriage-strap *e'* is wound is cylindrical in outline, the slots or seats *f* are uniformly spaced upon the periphery of disk *F*; but if, as in the instance shown, the drive-drum *E* is cam-shaped in outline the seats
60 must be variably spaced, as indicated in Fig. 2, in order to properly correspond with the vari-

ous letter-space positions of the carriage. The stop-supporting disk *F* is preferably adjustably fixed to the end of shaft *17* and for this purpose is provided with a conical central bore snugly fitting a corresponding cone-shaped section *39* of the shaft and is firmly but adjustably held in position by a lock-nut *40*. By thus adjustably connecting the stop-supporting disk to the carriage its notches or seats may be caused to register accurately with the letter-space scale which indicates the position of the carriage. Stops *G* are inserted in seats *f* from the rear in any desired position, with the working portion *g* of the stop projecting beyond the periphery of disk *F*, and are conveniently provided with projecting finger-pieces *g'*. The periphery of the disk *F* is preferably provided with a locking-ring *f'* of wire, held in place within a seat or groove near the inner face of the disk, and the stops *G* have notches *g*², arranged to engage the wire, so that they may be firmly held in position. The various stops *G* are thus independently adjustable and arranged to be set in adjusted position to define columnar positions at desired points along the line of print. For convenience in setting the stops the seats *f* for the column-stops are numbered from
70 "0" to "75" in correspondence with the marks upon the letter-space scale.

The drum or barrel *E* is provided with a section *E'*, over which is wound a second strap *e*², in a direction, however, the reverse of that in which the strap *e'* is wound upon the drum-section *E*. If the section *E* is cylindrical, the drum-section *E'* will be similarly shaped and of the same size; but if, as in this instance, it is cam-shaped the section *E'* will be correspondingly shaped and of the same size, but set in a reverse position. (See Fig. 4.) The strap *e*² extends from beneath the drum-section *E'* under a guide-pulley or idler *41* and over a guide-pulley *42*, and its free end is connected to the carriage-hook *25*, so that as the carriage is propelled by its spring in the direction of the line of print strap *e*² is unwound from the drum-section *E'*, while the strap *e'* is wound up upon the drum-section *E*. The guide-pulley *42* is properly positioned by a bracket *43*, which projects from the upper end of the rear right-hand corner-post *10* and upon the end of which the pulley *42* is journaled. Idler-pulley *41* is conveniently journaled upon the depending bracket *21*. It will be noted that stop member *F* is shiftably mounted upon the main frame of the machine independently of the carriage *B*, but that it is connected thereto so as to shift as the carriage travels in the direction of the line of print. Also by releasing the carriage and interposing suitable dogging means in the path of the stops *G* the carriage will be drawn rapidly in letter-space direction by spring *e*² and strap *e'*, but will be arrested at predetermined points when one of the stops is engaged by the dogging means through the medium of the stop-strap *e*².

The end of the shaft 17 affords a convenient mount for the ordinary warning-bell H, which is arranged to be struck by a tappet h, mounted upon the pivoted bar D. For convenience in adjusting the tension of the carriage-spring e a short stub-shaft 44, having a thumb-piece 45 on its outer end and a toothed wheel 46 on its inner end, is journaled in a bracket 47, fixed to the rear left-hand post 10. The stub-shaft 44 slides longitudinally through the bracket 47 and may be pushed inwardly to bring the toothed wheel into engagement with the ratchet-wheel 22 for winding up the carriage-spring e. Normally, however, the stub-shaft is held in outward position, with wheel 46 disengaged from ratchet 22 by a spring 48, coiled about the shaft and intermediate the bearing 47 and thumb-piece 45. The double retaining-pawl 23 is provided at its lower end with a laterally-extending portion 49, having a handle 50 and which projects beyond the edge of the stop-disk F, so as to be easily accessible for releasing the tension of drive-spring e.

25 A supporting-plate 51 is secured beneath stop-disk F by screws 52 to the horizontal plate a², formed upon the rearwardly-projecting portion of the base-frame A, and is provided with a central upwardly-extending boss 53, having a cylindrical bore. A cylindrical dog-carrier k is mounted to shift within the bore of the boss 53 and normally rests upon plate a². A stop block or dog K is fixed to the upper end of the dog-carrier k in line with the path of movement of the stops G and is preferably adjustable thereon in a direction tangential with such path of movement. For this reason the adjacent abutting faces of the dog-carrier and dog are provided with a corresponding series of interlocking teeth, (see Fig. 8,) and the fastening-screw 54 for holding the dog in place passes through a longitudinal slot 55 therein. (See Fig. 4.) By this adjustment the accurate arrest of the paper carriage at proper points is assured.

Dog-carrier k and dog K are shifted into the path of movement of the stops G by a rock-arm 56, which is fixed to and projects rearwardly from a short rock-shaft 57, with its free end engaging a longitudinal slot 58, formed in the dog-carrier k. Rock-shaft 57 is journaled within a bracket 57^a, fixed upon the front edge of frame section or plate a², and carries a forwardly-projecting rock-arm 59, which is pivoted at its free end to the upper end of a rigid link 60. The lower end of link 60 is pivoted to a key-lever M, which extends along one side of the main frame forwardly to the keyboard of the machine and is pivoted at its rear upon the common fulcrum 61 for the type-bar key-levers. The key-lever M is normally upheld by a spring 62, fixed to a cross-bar 63 and engaging the under side of the lever, in which position the free end of rock-arm 56 engages the lower end of slot 58 in the dog-carrier k and holds the latter and dog K in depressed position

out of the path of the stops G. One or more push-buttons or finger-keys N are mounted upon one side of the keyboard of the machine, 70 and their stems n are mounted to shift vertically through upright sleeves 64, formed upon a support 65, which is secured upon one side of the keyboard. The lower ends of push-key stems n are provided with contacts or 75 collars n', which are preferably adjustably threaded thereon and arranged to engage the forward end of spring-held key-lever M, by which the keys are normally upheld.

The column-field stops G are preferably of 80 different lengths—that is, their outer contact portions g, with which dog K engages, project outwardly to different distances from the periphery of the stop-disk F or are arranged in different paths of travel. The stops are arranged progressively, the shortest stop being the first one with which the dog may engage and the longest stop being the last one upon the periphery of the stop-disk. So, also, a series of keys N are preferably employed, corresponding in number to the different stops. Any desired number of stops and keys may be used, but in the present instance I have illustrated five different stops and keys. The downward movement of the keys N is limited 95 by their engagement with the upper ends of the supporting-sleeves 64, which thus act as stops to determine the extent of depression of the separate keys, and, as clearly indicated in Fig. 1, the sleeves are graded progressively, 100 so that varying extents of depression will be imparted by the variable throw of the several keys to the forward end of the key-lever M. Consequently the dog K will be shifted to varying positions, the parts being so designed that 105 such positions will correspond to the graded column-field stops G. Thus when any key is depressed dog K is shifted to proper position to engage the column-stop corresponding to that key, and when the carriage is released its 110 free run will be arrested at the desired columnar position or "field" upon the paper and the intermediate stops and column-fields will be skipped. In this way any predetermined one of a series of fields arranged along the 115 line of print and defined by the separate stops may be selected by a single operation of the spacing mechanism. It will be noted (see Figs. 4 and 9) that the slot 58 in dog-carrier k is of considerably greater width than 120 the end of the operating rock-arm 56, so that before the dog-carrier and the dog K are shifted the lost motion between the end of the rock-arm and the top of slot 58 must be taken up. The throw, however, of the key-lever M is sufficient to take up this lost motion and, in addition, shift the dog to the desired position. The separate field-stops G are independently adjustable and arranged to set in adjusted position, as described, upon the 125 stop-disk F, so as to define the size and location of the different fields arranged along the line of print in keeping with the desired arrangement upon the paper.

130

To lock dog K in any of its shifted positions, a check-pawl 66 is pivoted within a slot cut in the side of the boss 53, and a coiled spring 67, arranged beneath the tailpiece of 5 the pawl, is arranged to force its upper end into engagement with a series of teeth 68, cut upon the side of the dog-carrier k. Thus when any key is depressed and dog K shifted pawl 66 engages one of the teeth 68 and 10 locks the dog in position, so that the operator need not hold down the selected key. The latter, however, together with the key-lever M, is returned part way to normal position as soon as released to the extent permitted 15 by the lost motion between the end of the rock-arm 56 and the dog-carrier k.

A rod 69 is pivoted at its lower end to the rock-arm 56 and is guided at its upper end within an eye or bearing 70, formed upon a 20 plate 71, which projects rearwardly from top plate a and is secured thereto by a stub-bolt 71^a. Rod 69 is bent or offset, as shown in Fig. 4, so that it will reciprocate vertically through the eye or bearing 70. A split supporting-lug 72 is fixed to rod 69 near its upper end, to which is pivoted an upwardly-extending latch or pawl 73, normally pressed by a flat spring 74 against the tail of a pawl 75. The latter is pivoted upon a downwardly-extending lip or projection 76 upon the end of plate 71 and has at its upper end a notch or shoulder 77, which normally engages the rear end of a release-lever P. A bent-strip spring 78 is fixed to a lug 79 on pawl 75 near 25 its pivot and extends downwardly, then upwardly, and is provided with an inclined upper end which engages a pin or roller 80, fixed to the rear end of release-lever P. This spring serves to press the locking-pawl 75 toward 30 the end of release-lever P and to normally hold it into engagement therewith. The release-lever P is pivoted intermediate its ends upon a stud 81, which is fixed to an upright 35 82, rising from plate 71, and the forwardly-extending portion of the lever is provided with a releasing-plate p, which surrounds the pinion 30 and extends beneath the carriage-rack 27. A spring 83, coiled about the pivot-section of release-lever P, tends to hold its forward end in depressed inoperative position 40 and to return it to such position after it has been shifted to lift rack 27 out of engagement with pinion 31, and thus release the carriage. Release-lever P is of course normally locked 45 in its inoperative position by the engagement of the shoulder or notch 77 of pawl 75 with its rear end.

When any key N is depressed to actuate lever M and shift dog K, as described, rod 69 50 will be shifted by the rock-arm 57 to lift latch 73 and bring the shoulder 84 thereon above the tailpiece 85 of the locking-pawl 75. Then when the finger-key N is released by the operator although the dog K is locked in its shifted position by pawl 66 rock-arm 56, and 55 with it rod 69, will descend to the extent of the lost motion between the rock-arm 56 and

dog-carrier k, and the shoulder 84 on latch 73 will engage the tailpiece 85 of locking-pawl 75 and swing it about its pivot to release the lever P, as indicated in Fig. 7. By thus swinging locking-pawl 75 about its center the tension of spring 78 will be increased and will be sufficient to overcome the light spring 83, so that the outer or rear end of the release-lever P is depressed, its inner end lifted, and carriage-rack 27 thrown out of engagement with pinion 30, thus releasing the carriage for a free run until arrested by the engagement of one of the stops G with the dog K. When the locking-pawl 75 is thus swung out from beneath the rear end of release-lever P, its upper end will engage the upper end of latch 73, and thus serve to disengage the shoulder 84 of the latch and rod 69 may descend to the full extent permitted by the lost motion between rock-arm 56 and dog-carrier k.

It will be noted that in the normal position of the parts, as shown in Fig. 4, the shoulder 84 is positioned at a distance below the tailpiece 85 equal to the extent of this lost motion, so that the shoulder will be invariably brought above the tailpiece when any key is depressed. Moreover, this lost motion is equal to or greater than the greatest shift of the dog-carrier k, so that the latch 73 will descend through a sufficient extent to throw out the detaining-pawl 75 irrespective of the extent to which the dog K is shifted. By thus actuating the release-lever through the medium of the spring 78, which is previously placed under tension and permitted to act by the shift of locking-pawl 75, the carriage-rack 27 will be lifted quickly from engagement with pinion 30 irrespective of the speed of actuation of keys N by the operator—that is to say, the release mechanism although actuated by the operator is automatically controlled and there is no danger that the rack as the carriage travels quickly toward the left will scrape along the pinion 30 to injure or wear the intermeshing teeth. The split collar 72, upon which the releasing-latch 73 is pivoted, is held adjustably in position upon the rod 69 by a screw 86, extending between the split sections, so that the position of the latch may be adjusted to effect release promptly at the proper point. As soon as the release-lever P is actuated it is locked in its shifted position 105 by a pin 87, adjustably threaded through the end of a bell-crank 88. The latter is pivoted on a stud 89, rising from plate 71, and its spring 90 normally holds the pin 87 against the side of the outer end of lever P, but swings it over 110 the rear end of the lever as soon as the latter is depressed. The carriage is then free to run and is arrested in proper position. Moreover, since dog K is locked there is no danger that the shock of contact between the stops and 115 dog will throw the latter out of line and allow the carriage to run a step or two farther; but the latter will be invariably arrested at the desired position.

After the spacing mechanism has been operated as described at the next subsequent operation of any key to print a character the dog-rocker 36 swings forward in the usual manner, and a lug or projection 91 upon its upper end, (see Fig. 6,) which is arranged behind the end of one of the arms 92 of bell-crank 88, swings the latter to remove pin 87 from above the rear end of lever P. The latter is then returned to normal by spring 83 and locked by spring-pressed pawl 75, and carriage-rack 27 is permitted to reengage pinion 30. At the same time an arm 93, which is fixed to the pivoted section of dog-rocker 36 and inclined rearwardly and toward the left, engages tailpiece 94 of the locking-pawl 66 and throws the latter from engagement with the teeth 68 of the dog-carrier k. The latter, together with the stop-dog K, is returned to normal by the rock-arm 57, which, together with key-lever M and the finger-key N, is then free to be returned completely to normal position by spring 62. The finger-keys may then be manipulated in the usual manner to print characters in desired position upon the paper.

An arm 95, preferably of spring metal, is fixed to the rearwardly-extending arm 92 of bell-crank 88, and when the latter swings upon its pivot to lock the release-lever P the arm or detent 95 is shifted into engagement with the teeth of escapement-ratchet 33. Any accidental displacement or "overthrow" of the escapement-wheel and the pinion 30, connected thereto, when released from rack-bar 27 is thus prevented, and the latter when unlocked will reengage the pinion to hold the carriage in proper letter-space position. Detent 95 is of course returned to normal out of engagement with the escapement-wheel 33 when bell-crank 92 is shifted to normal position by the lug 91 on the dog-rocker.

Upon a bracket 96, depending from the rear end of the bearing 19, is pivotally supported, intermediate its ends, a brake-lever R, to the upper end of which is journaled a friction-roll r, arranged to bear upon a cylindrical friction-surface 97, formed upon the rear face of stop-disk F. The lower arm of brake-lever R is bent laterally and carries journaled on its end a bearing-roll 98, which is arranged to be engaged by cam-piece 99. The latter is fixed to the end of a stud 100, which is fixed upon dog-carrier k and preferably formed in piece therewith and which projects laterally through a vertical slot 101, formed in the side of the boss or bearing 53. The cam-piece 99 is provided with an incline face arranged to engage the roller 98, and the cam-piece is preferably split, as shown, and connected to the lug 100 by an adjusting-screw 102, so that the degree of inclination of the cam-surface may be adjusted. When the dog-carrier k is shifted by one of the finger-keys, the upward movement of the cam-piece 99 swings brake-lever R and brings its friction-roll r to bear upon the friction-surface 97. The too rapid movement of

the paper-carriage is thus checked and injurious shocks upon the parts when brought to rest by dog K avoided. It may also be noted that by connecting the stop member F to the carriage by a flexible stop-strap e² the shock upon the quickly-moving carriage is much less than when the stop member is directly mounted thereon.

The operation is obvious from the foregoing.

It will be understood that numerous modifications could be made by the skilled mechanic without departure from the spirit of the invention and that features of the invention could be used without its adoption as a whole.

The phrase "two-way connection" as used in some of the claims is intended to cover any suitable means for so connecting the shiftable stop-supporting device to the paper-carriage that they must necessarily both be arrested together and must necessarily shift in unison both during the letter-space movement of the carriage and during its return movement, in contradistinction to a one-way flexible connection between these parts, which would permit the carriage to overrun when the stop-support has been arrested or with which an independent spring or the like must be connected to the stop-support to take up the slack in the flexible connection during the return movement of the carriage.

Having described my invention, what I claim as new, and desire to secure by Letters Patent, is—

1. In spacing mechanism for type-writing machines, the combination with a carriage, of means for arresting the travel of said carriage comprising two elements, viz: a series of column-field stops and means for dogging said stops, the latter being adjustable and arranged to be set in adjusted position to define columnar points along the line of print and a shiftable part whereon one of said elements is mounted, said part being sustained on the main frame of the machine independent of said carriage but connected thereto to shift as the carriage travels in the direction of the line of print and means for effecting the engagement of said dogging means with a predetermined one of said column-field stops.

2. In spacing mechanism for type-writing machines, the combination with a carriage, of means for arresting the travel thereof comprising two elements, viz: a series of column-field stops independently adjustable to define various columnar positions and means for dogging said stops, a shiftable part whereon one of said elements is mounted, said part being sustained upon the main frame of the machine independent of said carriage but connected thereto to shift as the latter travels in letter-space direction and finger-key mechanism for effecting the engagement of said dogging means with a predetermined one of said column-field stops.

3. In spacing mechanism for type-writing machines, the combination with a carriage, of a driving member having a flexible driving connection and a reversely-arranged flexible stop connection with said carriage, and means for arresting the travel of said carriage comprising a series of stops and means for dogging said stops, one of said elements being mounted upon said driving member. 75
- 5 a series of column-field stops independently adjustable to define various columnar points arranged along the line of print and means for dogging said stops, a shiftable part whereon one of said elements is mounted, said part being sustained upon the main frame independent of said carriage but connected thereto to shift as the latter travels in letter-space direction, an escapement mechanism for said carriage, a releasing mechanism therefor and key-operative means arranged to actuate said release and to effect the engagement of said dogging means with a predetermined one of said column-field stops. 80
- 10 4. In spacing mechanism for type-writing machines, the combination with a carriage, of means for arresting its travel comprising two elements, viz: a series of adjustable stops and means for dogging said stops, a shiftable part whereon one of said elements is mounted, said part being sustained on the machine-frame independently of said carriage but having two-way connections with said carriage and moving in unison therewith in opposite directions, means for effecting the engagement 85 of said dogging means with said stops, and a series of grooves or seats corresponding to letter-space positions for said adjustable stops. 90
- 15 5. In spacing mechanism for type-writing machines, the combination with a carriage, of means for arresting its travel comprising two elements, viz: a series of stops and means for dogging said stops, a shiftable driving member sustained on the main frame independent of the carriage whereon one of said 95 elements is mounted and a positively-acting stop connection between said shiftable driving member and said carriage. 100
- 20 6. In spacing mechanism for type-writing machines, the combination with a carriage, of means for arresting its travel comprising two elements, viz: a series of independently-adjustable stops and means for dogging said stops and a shiftable driving member for said carriage whereon one of said elements is mounted, said driving member having a positively-acting stop connection with said carriage. 105
- 25 7. In spacing mechanism for type-writing machines, the combination with a carriage, of means for arresting its travel comprising two elements, viz: a series of independently-adjustable stops and means for dogging said stops, a shiftable driving member for said carriage whereon one of said elements is mounted, said driving member having a positively-acting stop connection with said carriage, an escapement mechanism for said carriage, a releasing mechanism therefor and key-operative means arranged to actuate said release and to effect the engagement of said dogging means with said stops. 110
- 30 8. In spacing mechanism for type-writing machines, the combination with a carriage, of a driving member having a flexible driving connection and a reversely-arranged flexible stop connection with said carriage, and means for arresting the travel of said carriage comprising a series of stops and means for dogging said stops, one of said elements being mounted upon said driving member. 115
- 35 9. In spacing mechanism for type-writing machines, the combination with a carriage, of a driving member having a flexible drive connection and a reversely-arranged stop connection with said carriage, means for arresting the travel of said carriage comprising a series of stops and means for dogging said stops, one of said elements being mounted upon said driving member, an escapement mechanism for said carriage, a releasing mechanism therefor and key-operative means extending to the keyboard of the machine and arranged to actuate said release to effect the engagement of said dogging means with said stops. 120
- 40 10. In spacing mechanism for type-writing machines, the combination with a carriage, of a shiftable member independently mounted upon the machine-frame but connected to the carriage to shift as the latter travels in letter-space direction, means for arresting the travel of the carriage comprising two elements, viz: a series of column-field stops and means for dogging said stops, the latter being adjustable and arranged to be set in adjusted position and to define columnar positions along the line of print, one of said elements being mounted upon said shiftable member and the other on the machine-frame and key-operative means arranged to variably shift 125 one of said elements to effect the engagement of said dogging means with a predetermined one of said column-field stops. 130
- 45 11. In spacing mechanism for type-writing machines, the combination with a carriage, of a shiftable member independently mounted upon the machine-frame but connected to the carriage to shift as the latter travels in letter-space direction, means for arresting the travel of said carriage comprising a series of independently-adjustable column-field stops and means for dogging said stops, one of said elements being mounted upon said shiftable member and the other on the machine-frame, an escapement for said carriage, a releasing mechanism therefor and key-operative means arranged to actuate said release mechanism to variably shift said dogging means to effect the engagement of the latter with a predetermined one of said column-field stops. 135
- 50 12. In spacing mechanism for type-writing machines, the combination with a carriage, of a shiftable member sustained upon the machine-frame independent of said carriage but connected thereto to shift as the carriage travels in letter-space direction and means for arresting the travel of said carriage comprising a series of column-field stops adjust- 140

ably mounted upon said shiftable member and arranged to be set in adjusted position and means arranged for dogging a predetermined one of said column-field stops.

- 5 13. In spacing mechanism for type-writing machines, the combination with a carriage, of a shiftable member sustained upon the machine-frame independent of said carriage but connected thereto to shift as the carriage travels in letter-space direction, means for arresting the travel of said carriage comprising a series of independently-adjustable column-field stops mounted upon said shiftable member, a dog for engaging said stops and key-operative means extending to the machine-keyboard and arranged to effect the engagement of said dog with any predetermined one of said column-field stops.
- 10 14. In spacing mechanism for type-writing machines, the combination with a carriage, of a shiftable member having a series of grooves or seats corresponding to letter-space positions sustained independently of said carriage but positively connected thereto to shift as the latter travels in opposite directions and means for arresting the travel of said carriage comprising a stop adjustably mounted on said grooves or seats of said shiftable member and a dog mounted upon the machine-frame and key-operative means arranged to effect the engagement of said dog with said stops.
- 15 15. In spacing mechanism for type-writing machines, the combination with a carriage, of a shiftable member sustained independently of said carriage but positively connected thereto to shift as the latter travels in opposite directions and means for arresting the travel of said carriage comprising, viz: a series of independently-adjustable stops mounted on said shiftable member and means for dogging said stops mounted on the machine-frame and key-operative means extending to the keyboard of the machine and arranged to shift said dogging means to effect the engagement thereof with said stops.

- 20 16. In spacing mechanism for type-writing machines, the combination with a carriage, of a shiftable driving member having a positively-acting stop connection therewith and means for arresting the travel of said carriage comprising a series of independently-adjustable stops mounted upon said driving member, means for dogging said stops and key-operative means arranged to effect the engagement of said dogging means with said stops.
- 25 17. In spacing mechanism for type-writing machines, the combination with a carriage, of a driving member having a flexible driving connection and a reversely-arranged flexible stop connection with said carriage, a series of column-stops mounted upon said driving member, means for dogging said stops mounted on the machine-frame and key-operative means arranged to shift said dogging

means to effect the engagement of the latter with said stops.

18. In spacing mechanism for type-writing machines, the combination with a carriage, of a shiftable member sustained independent of the carriage but connected thereto to shift as the carriage travels in letter-space direction, means for arresting the travel of said carriage comprising two elements, viz: a series of column-field stops mounted upon said shiftable member and means for dogging said stops, and means for shifting one of said elements to effect the engagement of said dogging means with a predetermined one of said column-field stops.

19. In spacing mechanism for type-writing machines, the combination with a carriage, of a shiftable member sustained independent of the carriage but connected thereto to shift as the carriage travels in letter-space direction, means for arresting the travel of said carriage comprising two elements, viz: a series of graded column-field stops having their contact portions in different paths of travel and means for dogging said stops, one of said elements being mounted on said movable member and the other on the machine-frame, and means for effecting the engagement of said dogging means with a predetermined one of said graded column-field stops.

20. In spacing mechanism for type-writing machines, the combination with a carriage, of a shiftable member sustained independent of the carriage but connected thereto to shift as the carriage travels in letter-space direction, means for arresting the travel of said carriage comprising two elements, viz: a series of independently-adjustable graded column-field stops mounted upon said shiftable member and having their contact-faces in different paths of travel and means for dogging said stops, and key-operated mechanism for effecting the engagement of said dogging means with a predetermined one of said column-field stops.

21. In spacing mechanism for type-writing machines, the combination with a carriage, of a power-propelled driving member, said member having two-way connections with said carriage to travel in unison therewith in opposite directions, means for arresting the travel of said carriage comprising a series of independently-adjustable stops mounted on said driving member and means for dogging said stops mounted on the machine-frame.

22. In spacing mechanism for type-writing machines, the combination with a carriage, of a rotatable part mounted on the machine-frame and connected to said carriage and means for arresting the travel of the latter comprising two elements, viz: a series of column-field stops and means for dogging said stops, the latter being adjustable and arranged to be set in adjusted position, one of said elements being mounted upon said rotatable member, and means for effecting the engage-

ment of said dogging means with any predetermined one of said column-field stops.

23. In spacing mechanism for type-writing machines, the combination with a carriage, of a rotatable member mounted on the machine-frame and connected to the carriage, a series of column-field stops mounted upon said rotatable member, means for dogging said stops and key-actuated devices for effecting the engagement of said dogging means with any predetermined one of said column-field stops.

24. In spacing mechanism for type-writing machines, the combination with a carriage, of a rotatable member mounted on the machine-frame and connected to the carriage, of means for arresting the travel of said carriage comprising a series of stops and means for dogging said stops, a support for said stops 20 rotatably adjusted on said rotatable member and key-operated means arranged to effect the engagement of said dogging means with said stops.

25. In spacing mechanism for type-writing machines, the combination with a carriage, of a rotatable member mounted on the machine-frame, said rotatable member having two-way connections with said carriage to travel in unison therewith in opposite directions, 30 means for arresting the travel of said carriage comprising a series of stops and a dog for engaging said stops, a series of grooves or seats for receiving said stops formed on said rotatable member and corresponding to the various 35 letter-space positions and finger-key mechanism for shifting said dog to engage said stops.

26. In spacing mechanism for type-writing machines, the combination with a carriage, of a rotatable power-propelled member mounted 40 on the machine-frame, said driving member having two-way connections with said carriage to travel in unison therewith in opposite directions, means for arresting the travel of said carriage comprising a series of independently-adjustable stops and means for dogging said stops, one of said elements being mounted on said rotatable driving member.

27. In spacing mechanism for type-writing machines, the combination with a carriage, of 50 a rotatable power-propelled drum having a flexible driving connection with said carriage and a reversely-wound stop connection therewith, means for arresting the travel of said carriage comprising a series of stops and 55 means for dogging said stops, one of said elements being connected to said rotatable drum and the other being mounted on the machine-frame, and finger-key mechanism for shifting said last-mentioned element to effect the engagement of said dogging means with said stops.

28. In spacing mechanism for type-writing machines, the combination with a carriage, of a rotatable power-propelled drum having a 65 flexible driving connection with said carriage and a reversely wound and arranged stop connection therewith, means for arresting the

travel of said carriage comprising a stop-disk adjustably connected to said drum, a series of adjustable stops upon said stop-disk, 70 means for dogging said stops mounted upon the machine-frame and key-operated devices for shifting said dogging means to engage said stops.

29. In spacing mechanism for type-writing machines, the combination with a carriage, of a power-propelled driving-drum therefor having duplicate reversely-arranged cam-sections, flexible drive and stop straps reversely wound upon said duplicate cam-sections and 80 connected to said carriage, a series of column-stops and means for dogging said stops, one of said elements being connected to said drum and the other being mounted upon the machine-frame and means for effecting the engagement of said dogging means with said stops.

30. In spacing mechanism for type-writing machines, the combination with a carriage, of a rotatable member mounted on the machine-frame independently of said carriage but connected thereto to shift as the latter travels in letter-space direction, the shaft of said rotatable member having a conical section, a stop-supporting disk having a correspondingly-shaped bore adjustably mounted on the conical section of said shaft, a lock-nut for holding said disk in adjusted position, a series of seats or grooves in the periphery of said disk corresponding to various letter-space positions, a series of column-stops set in adjusted position within said seats and a shiftable dog mounted on the machine-frame arranged to engage said stops.

31. In spacing mechanism for type-writing machines, the combination with a carriage, of a rotatable member mounted on the machine-frame and having a stop connection with said carriage, means for arresting the travel of the latter comprising two elements, 110 viz: a series of column-field stops and means for dogging said stops, one of said elements being mounted on said rotatable member and key-operated means extending to the machine-keyboard for effecting the engagement of said 115 dogging means with a predetermined one of said column-field stops.

32. In spacing mechanism for type-writing machines, the combination with a carriage, of a rotatable stop-disk mounted on the machine-frame and connected to said carriage, a series of graded column-field stops mounted on said stop-disk, means for dogging said stops and means for variably shifting said dogging means to effect the engagement thereof with a predetermined one of said column-field stops.

33. In spacing mechanism for type-writing machines, the combination with a carriage, of a rotatable driving-drum having flexible 130 driving and stop connections with said carriage, escapement mechanism for said carriage and releasing means therefor, a series of graded column-field stops adjustably

mounted upon said driving-drum, a dog on the machine-frame for engaging said stops and key mechanism arranged to variably shift said dog to engage any predetermined 5 one of said stops.

34. In spacing mechanism for type-writing machines, the combination with a carriage, of a shiftable member sustained independently of said carriage but connected thereto 10 to shift as the latter travels in letter-space direction, means for arresting the travel of said carriage comprising a series of stops and dogging means for engaging said stops, one of said elements being mounted upon said 15 shiftable member, key mechanism for shifting one of said elements to effect the engagement of said dogging means with said stops and means automatically operating to detain said element in shifted position inde- 20 pendently of said key mechanism.

35. In spacing mechanism for type-writing machines, the combination with a carriage, of a shiftable member sustained independently of said carriage but connected thereto 25 to shift as the latter travels in letter-space direction, means for arresting the travel of said carriage comprising a series of stops and dogging means for engaging said stops, one of said elements being mounted upon said 30 shiftable member, key mechanism for shifting one of said elements to effect the engagement of said dogging means with said stops, means automatically operating to lock said element in shifted position and a release for 35 said lock actuated by the printing mechanism of the machine.

36. In spacing mechanism for type-writing machines, the combination with a carriage, of a shiftable member sustained independently 40 of said carriage but connected thereto to shift as the latter travels in letter-space direction, of means for arresting the travel of said carriage comprising two elements, viz: a series of column-field stops and means for dogging 45 said stops, one of said elements being mounted upon said shiftable member and the other upon the machine-frame, means for variably shifting one of said elements to effect the engagement of said dogging means with a pre- 50 determined one of said column-field stops and a lock for detaining said element in any one of its shifted positions.

37. In spacing mechanism for type-writing machines, the combination with a carriage, of 55 a rotatable stop-disk sustained on the machine-frame independent of said carriage but having a stop connection therewith, a series of column-stops mounted upon said disk, a dog for engaging said stops, actuating key mech- 60 anism for shifting said dog, a lock for detaining said dog in its shifted position and an arm upon the escapement-dog rocker of the machine for releasing said lock.

38. In spacing mechanism for type-writing 65 machines, the combination with a carriage, of a shiftable member sustained independently of the carriage but connected thereto to shift

as the latter travels in letter-space direction, means for arresting the travel of said carriage comprising two elements, viz: a series of column-field stops and means for dogging said stops, means extending to the keyboard of the machine for effecting the engagement of said dogging means with a predetermined one of said column-field stops and a series of 70 finger-keys for actuating said means. 75

39. In spacing mechanism for type-writing machines, the combination with a carriage, of a rotatable stop-disk having a stop connection with said carriage, a series of graded column-field stops adjustably mounted on said stop-disk, a dog for engaging said stops mounted on the machine-frame, a key-lever for shifting said dog and a series of finger-keys arranged to variably shift said key-lever to 80 effect the engagement of said dog with a predetermined one of said stops. 85

40. In spacing mechanism for type-writing machines, the combination with a carriage, an escapement mechanism and a releasing mech- 90 anism therefor, of a rotatable stop-disk having a stop connection with said carriage, a series of graded column-field stops mounted on said disk, a dog for engaging said stops mounted upon the machine-frame, a key-lever for shifting said dog and for actuating said release and a series of finger-keys for variably shifting said key-lever to effect the engagement of said dog with any predetermined 95 one of said stops. 100

41. In spacing mechanism for type-writing machines, the combination with a carriage, of means for arresting its travel comprising two elements, viz: a series of column-field stops and means for dogging said stops, and actuating devices comprising a series of finger-keys of variable throw arranged to variably shift one of said elements to effect the engagement of said dogging means with a predetermined one of said stops. 105 110

42. In spacing mechanism for type-writing machines, the combination with a carriage, of means for arresting its travel comprising two elements, viz: a series of column-field stops and means for dogging said stops, and actuating devices comprising a series of finger-keys and a series of graded stops arranged to variably limit the throw of the several keys, whereby one of said elements is variably shifted to effect the engagement of said dogging 115 means with a predetermined one of said stops. 120

43. In spacing mechanism for type-writing machines, the combination with a carriage, of means for arresting its travel comprising a series of graded column-field stops arranged 125 to shift with said carriage, a dog for engaging said stops, a key-lever for shifting said dog, a series of finger-keys for actuating said lever and a series of graded, supporting stop-sleeves for said finger-keys arranged to variably limit the throw thereof, whereby said dog will be variably shifted to engage any predetermined one of said stops. 130

44. In spacing mechanism for type-writing

machines, the combination with a power-propelled carriage, an escapement and a release therefor, of means for arresting the travel of said carriage comprising a stop and a dog for 5 engaging said stop, and a key-operated reciprocating member arranged to move one of said parts to position to engage the other during the forward movement of said member and to actuate said release during the return 10 movement thereof.

45. In spacing mechanism for type-writing machines, the combination with a power-propelled paper-carriage, an escapement and a release therefor, of means for arresting the 15 travel of said carriage comprising two elements, viz: a series of stops and means for dogging said stops, a key-operated reciprocating member having a lost-motion connection with one of said elements and arranged 20 to move the same to engage the other of said elements during the forward movement thereof, a lock for retaining said element in its shifted position and a trip on said reciprocating member arranged to actuate said release during 25 the return movement thereof.

46. In spacing mechanism for type-writing machines, the combination with a power-propelled paper-carriage, an escapement and a release therefor, means for arresting the travel 30 of said carriage comprising two elements viz: a series of stops and means for dogging said stops, a key-operated reciprocating member, a rock-shaft operated thereby and having a lost-motion slot connection with one of said 35 elements and arranged to move the same to engage the other of said elements during the forward movement of said member, a lock for retaining said element in shifted position and a spring-pressed latch operated by said 40 member and arranged to actuate said release during the return movement thereof.

47. In spacing mechanism for type-writing machines, the combination with a power-propelled paper-carriage, an escapement and a release therefor, of a shiftable member connected to said carriage, a series of adjustable 45 stops mounted thereon, a dog for engaging said stops, a key-lever, a rock-arm actuated thereby having a lost-motion slot connection 50 with said dog and arranged to shift the latter to engage said stops as said key-lever is depressed, a spring-held pawl for locking said dog in shifted position, a shiftable part connected to said rock-arm and a spring-held 55 latch thereon arranged to actuate said release as said key-lever is permitted to return to normal.

48. In spacing mechanism for type-writing machines, the combination with a power-propelled paper-carriage, an escapement and a release therefor, of means for arresting the travel of said carriage comprising two elements, viz: a series of stops and means for dogging said stops, a braking device, a key-operated reciprocating member arranged to move one of said elements to engage the other and to apply said braking device during its

forward movement, said member having a lost-motion connection with said parts, a lock for detaining said parts in shifted position and a trip operated by said member and arranged to actuate said release during the return movement thereof. 70

49. In spacing mechanism for type-writing machines, the combination with a carriage, an escapement and a release therefor, of means for arresting the travel of said carriage comprising two elements, viz: a series of stops and means for dogging said stops, a key-operated reciprocating member having a lost-motion 75 connection with one of said elements and arranged to shift the same to engage the other of said elements during its forward shift, a lock for detaining said element in its shifted position, a trip operated by said member as 80 it returns to normal for actuating said release, a lock for detaining said release in operative position and means controlled by the printing mechanism of the machine for releasing both of said locks. 85

50. In spacing mechanism for type-writing machines, the combination with a carriage, an escapement and a release therefor, of means for arresting the travel of said carriage comprising a stop-disk, a series of stops and a braking-surface mounted on said disk, a dog for engaging said stops and a brake for engaging said surface carried on the machine-frame, a brake-actuator, a key-operated rock-arm having a lost-motion slot connection with said dog and said brake-actuator arranged to move said dog to engage said stops and to apply said brake during its forward movement, a lock for detaining said dog and brake-actuator, a rod connected to said rock-arm and a spring-pressed latch carried upon said rod and arranged to actuate said release during the return movement of said rock-arm. 95 100 105

51. In spacing mechanism for type-writing machines, the combination with a carriage, an escapement therefor, of means for arresting the travel of said carriage comprising a series of stops and means for dogging said stops, a release-lever for said escapement, a locking-pawl for holding said release-lever 110 out of operation, an actuating-spring extending between said pawl and said lever, key-operated devices for effecting the engagement of said dog with said stops and a trip actuated by said devices and arranged to throw said locking-pawl and place said spring under tension to throw said release-lever. 115 120

52. In spacing mechanism for type-writing machines, the combination with a carriage and an escapement therefor, of means for arresting the travel of said carriage comprising a series of stops connected to said carriage to shift as the latter travels in letter-space direction, a dog mounted on the machine-frame for engaging said stops, a pivoted release-lever for said escapement, a pivoted locking-pawl for holding said lever out of operation, a bent actuating-spring fixed to said pawl engaging the end of said lever, a key- 125 130

operated reciprocating member having an arm for moving said dog to engage said stops and a spring-pressed latch connected to said member and arranged to shift said pawl and to place said spring under tension to throw said release-lever.

53. In spacing mechanism for type-writing machines, the combination with a carriage, an escapement and a release therefor, of means for arresting the travel of said carriage comprising two elements, viz: a series of stops and means for dogging said stops, a key-actuated reciprocating member arranged to be shifted from normal to move one of said elements to engage the other and a trip adjustably connected to said member and arranged to actuate said release during the return movement thereof.

54. In spacing mechanism for type-writing machines, the combination with a power-propelled paper-carriage, an escapement and a release therefor, of means for arresting the travel of said carriage comprising a series of stops and means for dogging said stops, a brake for controlling the travel of said carriage, an adjustable shifter-cam for engaging said brake and key mechanism arranged to effect the engagement of said dogging means with said stops, to shift said brake-cam and to actuate said release.

55. In spacing mechanism for type-writing machines, the combination with a power-propelled paper-carriage, an escapement and a release therefor, of means for arresting the travel of said carriage comprising a series of stops and means for dogging said stops, a rotatable member mounted on the machine-frame and arranged to shift as said carriage travels in letter-space direction, a cylindrical brake-surface formed on said member, a pivoted brake-lever having means for engaging said surface, a shifter for said brake-lever, a cam-piece adjustably secured to said shifter and having an inclined face for engaging the end of said brake-lever and key mechanism arranged to effect the engagement of said dogging means with said stops and to actuate said shifter and said release.

56. In spacing mechanism for type-writing machines, the combination with a carriage, an escapement and a release therefor, of means for arresting the travel of said carriage comprising a rotatable driving-drum

having a flexible driving connection and a reversely-arranged flexible stop connection with 55 said carriage, a stop-disk fixed to the shaft of said drum, a series of column-stops adjustable upon the periphery of said disk to define various letter-space positions, a cylindrical brake-surface formed on said disk, a pivoted 60 brake-lever having means for engaging said surface, a dog for engaging said stops, a dog-carrier whereon said dog is mounted, a cam-piece mounted on said dog-carrier for engaging said brake-lever and a key-lever arranged 65 to actuate said dog-carrier and said release.

57. In spacing mechanism for type-writing machines, the combination with a column-stop support provided with a series of grooves or seats corresponding to letter-space positions, of a series of stops adjustably mounted on said support and a separate fixed locking-piece extending across said series of groups or seats upon said support for locking said stops in adjusted position.

58. In spacing mechanism for type-writing machines, the combination with a column-stop support provided with a series of grooves or seats corresponding to letter-space positions, of a series of stops adjustably mounted 80 on said support and a fixed locking-piece of spring metal on said support arranged to engage notches in said stops for holding the latter in adjusted position.

59. In spacing mechanism for type-writing machines, the combination with a column-stop support provided with a series of grooves or seats corresponding to letter-space positions, of a series of stops adjustably mounted on said support and a locking-wire extending 90 across said grooves or seats and arranged to engage notches in said stops for holding the latter in adjusted position.

60. In spacing mechanism for type-writing machines, the combination with a rotatable 95 stop-disk having a series of grooves or seats in its periphery, of a series of column-stops adjustable upon said disk and a locking-ring of spring-wire extending across said grooves or seats and arranged to engage notches in 100 said stops for holding the latter in adjusted position.
